219,840

CASSETTE OPERATED AUDIO-VIDEO PROJECTION CABINET OR SIMILAR ARTICLE

Masayuki Sakuma, Tokyo, Japan, assignor to
Kabushiki Kaisha Ricoh

Filed May 20, 1969, Ser. No. 17,245

Term of patent 7 years

Int. Cl. D16—04

U.S. Cl. D61—1

FIG. 1

FIG. 2

FIG. 3

FIG. 1 is a top, front perspective view of a cassette operated audio-video projection cabinet or similar article incorporating my new design;

FIG. 2 is a bottom, rear perspective view as seen from the opposite side of FIG. 1;

FIG. 3 is a side view thereof.

Portions of the drawing figures are shaded to indicate contrast in appearance, and portions are diagonally lined to indicate transparency.

I claim:

The ornamental design for a cassette operated audio-video projection cabinet or similar article, as shown and described
